CLOCK

Ralph Magro and Frank Grosse Borger, Jersey City, N. J.; said Magro assignor of a one-fifth interest to C. Edward Schlich, Jersey City, N. J.

Application June 22, 1933, Serial No. 677,100

2 Claims. (Cl. 58—38)

The invention relates to clocks, and particularly to electric driven clocks.

Pursuant to the invention indication of time is had by the combinational assembly of a hollow 5 rotary member bearing hour indications, an associated hollow rotary member bearing minute indications, indicator means suitably arranged relative to the hour and minute members to afford reading of time at any instant given by the 10 clock, the hour and minute members being of translucent material.

The clock mechanism per se is preferably actuated by alternating electric current, the supply of which is equipped with a current frequency time 15 control mechanism, as is well known to those skilled in the art.

In general, the invention in the preferred form, comprises in combination with the above stated hour and minute members and associated time 20 indicator means, an electric motor having provision of means for predetermining its absolute rate of rotation; the rotor of such motor being preferably mounted to rotate on a horizontal axis, a train of coordinated gearing yielding proportional rate of movement corresponding to hour 25 and minute values, a hollow stem serving as a support for the minute member and rotated in correspondence to minute time value, and includes a circuit for the driving electric motor, and terminals for the circuit means for connection with the house or other supply circuit.

More particularly, the preferred form of the invention, comprises an alarm device operatively 30 conditioned by the setting member, as by rotary movement of the setting member.

Desirably, the alarm effecting means comprises tonal elements of or embodying soft iron, arranged within the path of magnetic flux of the electric motor, the tonal elements being relatively 40 displaceable and capable of being brought into mutual physical contact during the stage of non-operative condition of the alarm, and separable during the stage of operative condition. Associated therewith are a dial and an indicator which 45 is manually set for the desired time of alarm release.

Further features and objects of the invention will be more fully understood from the following detail description and the accompanying 50 drawings, in which

Fig. 1 is a perspective view of a preferred form of the invention.

Figure 2 is a vertical sectional elevation on an 55 enlarged scale on line 2—2 of Figure 1.

Figure 3 is a vertical sectional view on an enlarged scale on line 3—3 of Figure 1.

Figure 4 is a vertical sectional view on line 4—4 of Figure 3.

Figure 5 is a vertical sectional view on line 5—5 5 of Figure 4.

Figure 6 is a vertical sectional view on line 6—6 of Figure 3.

Figure 7 is a vertical sectional view on line 7—7 10 of Figure 3.

Figure 8 is a detail plan view of the alarm setting dial and indicator.

Figure 9 is a diagram of the electrical circuit of the essential parts.

The drawings illustrate a preferred form of the 15 invention with respect to outer configuration, indication of nature of materials employed and with respect to the assembly and component parts of the operating mechanisms. However, those skilled in the art upon understanding the principles of the invention will readily perceive variations and modifications of the illustrated detail parts and assembly, and we contemplate all variations and modifications properly within the objects and purposes of our invention. 20 25

As illustrated in Fig. 1, the general configuration is hexagonal. As illustrated, the base 10, pedestal 11, the lower hollow hour member 12 and the upper hollow minute member 13 are shown of hexagonal character, certain of the same being 30 modified by frusto-conical contour.

As indicated above, the hollow hour member 12, shown lowerly of and the hollow minute member 13 are of translucent material. Glass is a suitable material for the members 12, 13. The glass may 35 be rendered "frosted" and/or tinted with color, singly or polychromed as desired. Wood is a suitable material for the base 10 and pedestal 11.

The time indicator is shown in the form of a double pointed or arrowed indicators 14, 15, the 40 former indicating the hour and the latter indicating the minute. The indicators 14, 15 may be secured to or integral with a band 16 which encircles closely about but spaced from the contiguous upper edge 12a of the lower hollow member 12 and the lower edge 13a of the upper hollow member 13, thus enabling the edges 12, 13a, to be spaced from one another for the purpose of eliminating unnecessary friction. The indicator band 16 is shown stationarily supported by the 45 respective oppositely disposed arms 17, 17, the lower ends of which are secured to the ring 18, secured to the upper end of the pedestal 11.

The upper hollow time member 13 is removably secured to the upper end of the vertical bracket 55

19, see Fig. 2, which bracket 19 is lowerly secured to the lamp receptor 20, the lamp receptor 20 being secured to and rotated by the hollow stem 21, serving also for receiving and protecting the conductors 22, 23, leading to the usual or other approved lamp socket 24. An electrical lamp 25, of the filament type, is shown positioned in the lamp socket 24.

10 The connection of the hollow time member 13 with the bracket 19 may be had, as shown, by means of a set screw 26, the head of which is preferably ornamented, the threading of the screw 26 being received in a suitable threaded opening at the top of the bracket 19.

15 The lower, in this instance, the hour member 12 is shown supported and rotated by the hollow sleeve 27, which surrounds the sleeve 21.

20 Preferably, the outer sleeve 27 is provided with an enlarged receptor head 28, suitable for removably receiving the lower circular edge portion 25 of the lower hollow member 12.

25 As shown, the sleeve 21 is rotated in correspondence to minute time rate and the outer sleeve 27 rotated in correspondence to hour time rate, see Fig. 3 and Fig. 4, as will hereinafter be more fully understood.

30 The removability of the respective hollow members 12, 13 facilitates the assembly of these parts, as well as of the lamp 25, and also affords access to the respective parts in the event of replacement.

35 Preferably, the hollow stem 21, see Fig. 4, extends at its lower end proximate the upper plate of the frame 29 of the clock mechanism, the lower end of the stem 21 being secured to and rotated by the hollow elongated cup member 30, which member 30 is provided with a sleeve 30A of electrically insulating material, thus enabling the hollow stem 21 to be made of metal. The securingment of the lower end of the stem 21 to the cup member 30 is shown had by a pin 31 secured to and extending laterally from the member 30, above the frame 29, and an open-ended slot 32 receiving the pin 31, thus forming a combined key and disconnectible connection.

40 Secured to the exterior of the sleeve 30A on the cup member 30 is a ring 33, of electrically conducting material and a similar but spaced therefrom ring 34, also of electrical conducting material. The brush 35 is associated with the ring 33 and the brush 36 is associated with the ring 34. The electrical lead 37 is connected to the base of the brush 35 and the electrical lead 38 is connected through the switch 39 with the brush 36.

45 As appears more fully hereinafter, the switch 39 is preferably of the rotary type, and is arranged to be operated by the manual actuating member 40, see Figs. 1 and 3. The leads 37, 38 are respectively connected to the terminals 41, 42 of the lamp, which are connected, see Fig. 9, by the conductors 43, 44, usually in the form of a flexible electric cord to terminals connected to the house or other current supply.

50 The above stated electrical parts are indicated in the diagram in Fig. 9, the switch 39 being shown set in its closed position.

55 Fig. 9 also illustrates the electric connection of the electric, i. e., synchronous motor, comprising inter alia, field winding 45, the terminals of which are connected by the leads 46, 47 to the terminals 41, 42. The armature or rotor of the motor is indicated at 48, and the two pole pieces at 49, 50. The two laminated cores are designated 51, 52. The details of the construction of the synchronous motor are not described herein,

in that such details may be varied as desired, the essential so far as relates to our invention with respect to the driving motor is that the motor be electrically actuated or controlled. In commercial embodiments of our invention, standard alternating current motors are purchased, the preferred type embodying pole pieces provided with corrugated or equivalent pole faces, see 49a and 50a, see Fig. 7, the effective number of which may be blanked out to effectively control the speed of rotation of the armature under synchronous drive of the time controlled supply current in coordination with the gearing ratios of the respective hour and minute trains.

5 The hour train of gearing comprises the main shaft 55 which is provided with a worm 56, see Fig. 3, meshing with the worm wheel 57 or equivalent, carried by the shaft 58, at the lower end of which is the worm 59 meshing with a worm wheel 60, or equivalent, carried by the shaft 61 to which is secured the worm 62, see Fig. 4, meshing with the worm wheel 63, or equivalent.

10 The worm gear 63 is preferably frictionally secured to the cupped member 30 (with which the minute stem 21 is coupled, as aforesaid), to enable the hour and minute members 12, 13, to be manually set or reset to correct time. Such frictional connection may be in the form of a flat spring 64 or equivalent secured to the reduced end of the cupped member 30, thus providing for minute time actuation of the stem 21 and therewith of the minute hollow member 13.

15 The hour train of driving gears comprises the gear wheel 65, see Fig. 4, meshing with the gear 35 wheel 66 secured at the lower end of the shaft 67; at the upper end is secured the gear 68 meshing with the gear wheel 69 secured to the outer sleeve 27, carrying as aforesaid the hour hollow member 12.

20 The switch 39, as illustrated in Figs. 4 and 5, comprises a rotary member 70 of insulating material, shaped or provided with ratchet formations 71, shown six in number, the alternate three ratchet formations being enveloped by the three-pronged, ratchet contoured element 72 of electrically conducting material, held in position by the retaining spring 73. The brush 74 cooperates with the three-pronged element 72, the end of the brush being connected to the lead 38. The actuating parts of the switch 39 and the therewith associated position retaining means, as shown in Fig. 5, comprises the pawl member 75, biased by the spring 76, supported and socketed, see 77, at one end of the oscillating lever 78 pivotally connected to the rocker bar 79, see Fig. 3, suitably pivotally mounted in the clock frame 29; the rocker bar 79 is rocked by vertical reciprocation of the finger piece 40 within the slot 80 in the base 10. The spring 40b, see Fig. 7, is provided to return the finger piece 40 to its uppermost position, as indicated in Fig. 3.

25 To afford starting of the clock mechanism, we provide the starting rocking lever 81, see Fig. 3, having a finger piece 82; a flat spring 81a is connected to the lever 81, the end of the flat spring 81a functioning with the ratchet wheel 83 to rotate the shaft 55 in proper drive direction. The spring 81a is tensioned by the spring 81b, see Fig. 6, for slight frictional engagement with its ratchet wheel 83. The rocking lever 81 is pivotally freely mounted on the stud 84, and is returned to its initial or restarting position by the retractile spring 85, one end of which is

suitably fixed and its free end 85a passed about the rocking lever 81, see Fig. 3.

The illustrated alarm device is of the non-tactile type, that is, the type wherein the alarm is produced in a manner other than by striking the alarm element against or with a solid object. The said non-tactile alarm device comprises the alarm-effecting members 90, 91, an end portion thereof respectively connected to 10 and supported by laminated cores 51, 52 and preferably of soft iron to avoid permanent magnetization, the free ends 90a, 91a, being normally spaced from one another, see Fig. 7, in which normal position under current excitation of the 15 motor, including the cores and pole pieces, the free ends of the alarm members are vibrated. To effect silencing of the alarm members, we provide the multi-bent lever 92, its end 92a co-acting with a cam 93 mounted on the stem 40a 20 of the finger piece 40. Upon rotating the finger piece 40 to rotate the high point of the cam 93 into engagement with the lever 92, the end 91a of the alarm member 91 is brought into engagement with the free end 90a of the alarm member 90, thus silencing the alarm. Upon rotation of the finger piece 40 to free the cam from the 25 lever 92, the resiliency of the alarm member 91 relative to the alarm member 90 conditions the members 90, 91 to alarm position.

30 As noted in Fig. 1, see 40c, indications may be applied as on a face of the base 10, to indicate "on" and "off" positions of the alarm.

The time for alarm, as illustrated, is set by a manually settable index 94, see Fig. 8, and coacting time marked dial 95. The index 94 is suitably rotatably mounted on the lower plate of the frame 29, at the lower, knurled end 96, see Fig. 3, of a stud 97, carrying at an upper portion a cam control member 98, coacting with the short sleeve or cup member 99, provided with a notch 99a, the member 99 being biased downwardly by the resiliency of the alarm member 91, which dually functions as a spring. To the member 99, is secured the wheel 101, which meshes with the time gear 101a, the ratio of teeth and diameter being selected to effect a complete rotation of the wheel 101 each twelve hours. By setting in the direction indicated by the applied arrows, the index 94 to the desired time of alarm, given by the dial 95, the cam control member 98 is rotated relative to the sleeve member 99, thus freeing the cam 98 from the notch 99a, and elevating the member 99, under tension of the resiliency of the alarm member 91, thus dually silencing the alarm. Upon rotation of the wheel 101, by the clock drive, the cam control member 98 approaches and finally enters the notch 99a, and provided the finger piece 40 has been moved to

"on" position, the alarm members 90, 91, are electromagnetically vibrated.

Shutting off of the alarm is had by manually turning the finger piece 40 to its "off" position.

Automatic shutting off of the alarm is provided 5 by the continued rotation of the wheel 101, effected by clock movement, whereby the cam control member 98 gradually elevates the cup member 99, to force the alarm member 91 into engagement with the alarm member 90.

10 It will be observed that the setting member 40 is employed for the dual functions of controlling the lighting and non-lighting of the lamp, namely, by vertical reciprocal movement, and further for conditioning and disconditioning the alarm, 15 namely, by rotary movement.

Whereas we have described our invention by reference to specific forms thereof, it will be understood that many changes and modifications may be made without departing from the spirit 20 of the invention.

We claim:

1. The combination of an electric motor including core elements of magnetic material, non-tactile alarm elements of magnetic material respectively in electro-magnetic relation to said core elements, means for mounting said magnetic material alarm elements to each normally yield an alarm, means for rendering said magnetic material alarm elements non-operative, time proportioned train of gearing operatively connected to the rotor of the electric motor, hour and minute indicating means driven by said train of gearing, and manually settable means including a time indicating element for normally actuating 35 said alarm elements at pre-set times, said manually settable alarm means including an element in geared relation with the train of gearing for bringing the alarm elements into engagement with each other, thereby effecting the non-operation 40 of the alarm elements during the period in advance of the pre-set time of alarm.

2. The combination of an electric motor including core elements of a magnetic material, non-tactile alarm elements of magnetic material respectively in electro-magnetic relation to said core elements, time proportioned train of gearing operatively connected to the rotor of the electric motor, hour and minute indicating means driven by said train of gearing, means in geared 50 relation with the train of gearing normally effecting mutual engagement and consequent non-operation of the non-tactile alarm elements, and manually settable means including a time indicating element for rendering said alarm non-operation 55 effecting means non-operative at the pre-set time of alarm.

RALPH MAGRO. [I.S.]

FRANK GROSSE BORGER. [I.S.]
